UNITED STATES PATENT OFFICE.

EINAR MOLMARK, OF AMBRIDGE, PENNSYLVANIA.

SPACING-TABLE.

1,011,990.

Specification of Letters Patent.

Patented Dec. 19, 1911.

Application filed August 9, 1909. Serial No. 511,915.

To all whom it may concern:

Be it known that I, EINAR MOLMARK, a citizen of Norway, residing in Ambridge, in the county of Beaver and State of Pennsylvania, have invented certain new and useful Improvements in Spacing-Tables.

This invention relates to that class of spacing tables or parallel movers which are adapted to support and move or permit and 10 guide the movement of templets and plates, patterns and tools or other articles to be operated or operated upon in parallel relation to each other.

The principal object of the invention is to 15 provide a simple, economical and efficient spacing table or machine for moving templets and plates or other articles in parallel relation to each other and adapted to be used in connection with or form a part of 20 punching, forming, cutting, stamping or similar machines.

A further object is to provide suitable means for operating a spacing table or machine of the character indicated whereby 25 templets and plates or other articles may be automatically moved to a predetermined position or positions while in parallel relation to each other, by means of a suitable power.

30 Other and further objects of the invention will appear from an examination of the drawings and the following description and claims, said drawings being made a part of this specification.

35 The invention consists in the features, combinations, and details of construction herein described and claimed.

In the accompanying drawings Figure 1 is a plan view of a machine constructed in 40 accordance with my improvements as applied to or constituting an improved punching machine, the upper portion of the punch being omitted; Fig. 2, a front elevation of the same; Fig. 3, an end elevation of the 45 machine shown in Figs. 1 and 2; Fig. 4, an enlarged detail view in elevation of the mechanism or power device, for operating the movable frame and thereby automatically moving the templet and plate or other 50 articles in parallel relation to each other and to the desired predetermined position or positions; Fig. 5, a view in central sectional elevation of the power device or piston and cylinder mechanism and the means for 55 rotatably supporting the same shown in Fig. 4; Fig. 6, a view in side elevation of the

power device or cylinder shown in Figs. 4 and 5, and also in Figs. 1, 2 and 3, and showing the mechanism for operating the fluid-inlet valve; Fig. 7, a central sectional view in elevation of the fluid inlet valve and casing shown on a smaller scale in Figs. 3, 4, 5, and 6; Fig. 8, an enlarged detail view in central vertical section of the end of the piston rod, showing the finder or 65 mechanism for operatively connecting the piston with the movable frame or with the templet or similar device carried by the frame; Fig. 9, a perspective view of my improved mechanism without the power device; Fig. 10, a bottom plan view of a movable frame; Fig. 11, a detail view in elevation of a clamping device for holding templets, plates, patterns or the like in position upon the movable frame; Fig. 12, a detail 75 view in side elevation of one of the journal bearings for the rollers or revolving racks of the movable frame, showing the stationary rack tooth on the bottom portion of the bearing; Fig. 13, a detail view in end elevation of the journal bearing and rack tooth shown in Fig. 12; and Fig. 14, a view 80 in side elevation of a modified form of rack and journal bearing showing a plurality of rack teeth secured in fixed relation to the 85 movable frame.

In constructing a machine in accordance with my improvements I provide a plurality of elongated pinions or rollers *a* which are arranged in parallel relation to each other and all in the same plane, and journaled in suitable fixed supports or stationary bearings *b*. These stationary journal bearings may be of any desired ordinary and well known form and are mounted on suitable rigid or stationary supports such as I-beams *c* which are adapted to form a strong supporting frame. Legs *d* may be provided when desired, and the transverse frame members *c* may be connected by longitudinal frame members of any desired form. 95

The rollers *a* are each provided with longitudinally extending gear teeth or ribs *e*, and in large machines where great strength is required supporting idler rollers *f*, journaled in suitable stationary journal bearings *g* are mounted in supporting engagement with the central portions of the rollers *a*. The journal bearings for the rollers *f* are preferably in pairs adapted to hold a 100 plurality of the rollers *f* in toothed engagement with each of the rollers *a* on opposite 105

sides of the latter and in position to form both a support and brace therefor.

A movable frame or table *h*,—formed preferably of metal side-frame members *i* having a space therebetween and rigidly connected by means of transverse frame members *j*, which are also preferably of metal strips adapted to provide spaces *k* and *l*,—is provided with preferably a plurality of annular toothed rollers or rotary racks *m* each having its preferably annular teeth or ribs *n* in meshing engagement with one or more of the rollers *a*. These rollers or racks *m* are connected and movable with the movable frame *h* in parallel relation to each other and at right angles to the rollers *a*. They are mounted upon or beneath the frame *h* adjacent to its opposite sides in brackets or journal bearings *o* which are in fixed relation to the movable frame, so that the rollers *m* are immovable longitudinally with respect to each other and with respect to the movable frame. The teeth of the respective rollers or rotary racks *m* are directly opposite each other or in alinement and extend in parallel relation to the teeth or longitudinal ribs of the rollers *a*. The brackets *o* are each provided with a lower rack portion *p* each having one or more rack teeth *q* in rigid relation to the movable frame and adapted to mesh with the toothed rollers *a*. The inner edge of each of the side-frame members *i* is provided with an inwardly extending supporting flange *r* and the end-frame members *j* are each provided with a similar inwardly extending flange *s* for supporting in proper position in the spaces *k* and *l*, a templet *t* and a plate *u* respectively, or adapted to support a pattern and tool, or other article or articles to be operated or operated upon. Clamps *v* which may be of any desired ordinary or well known form, are arranged at suitable intervals along the edges of the movable frame or the spaces *k* and *l*, respectively, in position to engage and securely hold in place the templet and the plate to be punched, or other article or articles.

The supporting flanges, for supporting the edges of the templet and plate respectively, are parallel, and the inner edges of the frame members *i* and *j* respectively are provided with upwardly and downwardly extending inner surface portions adjacent to the flanges *r* and *s* respectively and forming shoulders *w* which extend above and parallel with said flanges. These shoulders *w* on the transverse frame members *j* are parallel and should be the same distance apart as the finder and punch or other tool when the finder is in normal position. The flanges *r* with their shoulders *w* adjacent to the spaces *k* and *l* respectively, should be in alinement, so that the plate and templet as well as the supporting flanges and guiding shoulders of the respective spaces *k* and *l* of the movable frame will be at all times in corresponding positions with relation to the normal position of the finder and the punch or other tool, respectively. The movable frame is thus adapted to be moved freely in any desired direction in one plane—preferably a horizontal plane—and is adapted to move a templet and plate, or a pattern and article to be operated upon in parallel relation, so that all corresponding parts of a templet and a plate respectively have a parallel movement, or are moved and guided in parallel paths. When the movable frame is moved longitudinally of the rollers *a* the rollers or revolving racks *m* on the movable frame revolve. When the frame is moved transversely of the rollers *a* the latter revolve, and when the movement is oblique in any direction both sets of rollers, in so far as they are in operative engagement, revolve. Friction is thus reduced to a minimum and it is possible to move the frame in any desired direction in a horizontal plane with great facility and in such a manner that the parallel movements and relation of corresponding parts of a templet and of a plate to be punched, or other articles to be operated or operated upon, may be maintained with accuracy and with a single movable table or frame. The table may be operated manually when desired, but I have provided a simple and effective mechanism whereby it may be operated by the application of power such as hydraulic power, compressed air, or other fluid pressure, or power. My improved device or mechanism for securing parallel motion of templet and plate, or the like, including the power device for operating the movable frame, is particularly adapted for use in shifting, supporting and punching duplicates or metal parts for heavy work, and for punching or making articles from or in accordance with a pattern or templet.

A punch or other tool 2 is mounted in a suitable support such as the upper jaw 3 of a punch press having a lower jaw 4 and a punch plate 5 supported by the latter below the movable frame above described and in a position which will permit the frame and the plate or other article *u* which is to be operated upon to be moved in any desired direction in a horizontal plane to any position which may be necessary in order to present any desired part of the plate or similar article in position to be operated upon by the punch or tool. Mounted upon a suitable stationary support 6—which may be in the form of a rigid bow formed of an I-beam and extending across and over the movable frame—is a stop 7. This stop, in this instance, consists of the end of the piston cylinder 8 which is rotatably supported in a position which will permit the movable

frame and thereby the templet or pattern or any desired part thereof to be moved to a position directly beneath or to be determined by the stop 7. The position of the stop 7 is constant with respect to the position of the punch or tool 2, and the cylinder 8 is supported by and in fixed relation to a rotary disk or turn-table 9 which is rotatably supported by a ring 10 which is in turn supported by the stationary bow 6 to which the ring is secured by means of bolts 11, or in any desired ordinary manner. The rotary disk thus forms a pivotal support for the piston cylinder 8, the pivotal center of which corresponds with or is directly over the stop 7 formed by the inner end of the piston cylinder. An upright fluid-supply pipe 12 located at the pivotal center of the disk and piston cylinder extends upward through the center of the disk and is connected with a suitable source of fluid supply or source of power, the lower end of said pipe communicating with the interior of the piston cylinder with which it is connected by means of the pipe 13. The fluid supply passage formed by the pipes 12 and 13 is controlled by a three-way cock or valve 14 having converging passages 15, 16 and 17, as shown in Fig. 7. The valve casing or elbow 18 is provided with a port 19 leading into the pipe 13 and thereby communicating with the interior of the piston cylinder, and has an outlet opening 20 which is adapted to communicate with the passage 17 when the inlet passage 15 is closed, thus forming an outlet from the piston cylinder through the pipe 13, port 19, passages 16 and 17 and outlet port 20 which is adapted to permit the escape of pressure fluid simultaneously with the closing of the inlet passage but prevent the escape of fluid when the inlet passage is open.

A lever 21 is operatively connected with the valve by means of the valve stem 22, as shown in Figs. 4 and 6. A piston 23 is mounted in the piston cylinder and is provided with a piston rod 24 having a depending end portion 25 in which is mounted a vertical and vertically movable finder or positioning bolt 26 having a handle 27. A cap 28 in the lower end of the piston is provided with a central perforation through which the finder extends, and an inner collar 29, on the bolt, serves to limit the downward or outward movement of the latter and engages a spiral spring 30 in the hollow depending portion of the piston rod. This spring encircles the bolt or finder and serves to yieldingly hold it in extended or lowered position and in engagement with the templet or with the movable frame. Transverse shoulders, arms or bosses 31 on the piston rod are adapted to engage the lever 21 as the piston approaches the end of its stroke, and thereby turn the valve 14 from the position in which it is shown in Fig. 7 in which the inlet to the piston cylinder is open, to a position in which the fluid inlet will be closed and the outlet from the piston cylinder will be opened. The position of the lever when the inlet passage is open is shown in dotted lines in Fig. 6, and its position when the inlet passage is closed and the outlet is open is shown in full lines in said figure. A stop 32 limits the movement of the lever 21 when the latter reaches the position shown in Fig. 6. The valve lever 21 is shown in dotted lines in Fig. 6 in the position which it occupies when the inlet valve 14 is in the position shown in Fig. 7 with the fluid inlet passage open and the fluid outlet passage closed.

In operation, the piston rod, with the finder or positioning bolt, is drawn out to extended position, the finder being inserted into a hole in the templet corresponding with the position of a hole to be punched in the plate, or corresponding with a part of the plate which is to be brought under the punch or tool. The valve lever is then turned by the operator to the position necessary to admit pressure fluid to the piston cylinder. The fluid forces the piston to the position shown in Figs. 5 and 6, with the finder directly beneath the center of the rotary disk or turn table, or in other words, to the pivotal center around which the piston cylinder rotates. The movable frame is thus moved to a corresponding position, for instance, from the position shown in dotted lines in Fig. 1 to the position shown in full lines in said figure. The operation of the piston by the fluid under pressure causes the transversely extending arms of the piston rod to operate the inlet-valve lever so as to close the inlet passage and open the outlet passage. The operation may then be repeated as often as desired until the movable frame is brought to the desired position either with each operation or step by step. The cylinder may be turned to any desired position or in any desired direction and will always move the frame or the part engaged by the finder to a given position, which is determined by the stop.

The manner of pivotally mounting the cylinder permits it to be moved in any direction in a horizontal plane, and permits the finder to be moved in any direction in a horizontal plane with respect to the stop. The punch, stamp, die or other tool is so arranged that it is in the same relation to the plate or other article to be operated on as the stop with relation to the templet, and the templet and plate are held and moved in parallel relation to each other, as the frame is moved from one position or any given position to another position parallel with respect to the position from which it is moved. The parallel relation of the tem-

plet and plate, and of the movable frame with respect to the stationary supports or any stationary object is thus maintained.

I claim:—

5. 1. In a device of the class described, the combination of a movable frame, and guiding mechanism comprising a toothed roller in toothed engagement with and extending at an angle with relation to an adjacent 70 relatively movable guiding member, and adapted to permit the movement of the frame from a given position to another position parallel to the position from which it is moved and hold it in such relatively 75 parallel positions.
2. In a device of the class described, the combination of a movable frame, rotary guides extending at an angle with relation to and in engagement with each other and 80 comprising a roller having peripheral teeth in meshing engagement with an adjacent guiding member, and means for supporting the rotary guides.
3. In a device of the class described, the combination of a movable frame, rotary guides having peripheral teeth in meshing engagement with each other and having their axial centers at right angles with respect to each other, said guides being adapted 90 to permit the movement of the frame to and hold it in different parallel positions, and means for supporting the guides.
4. In a device of the class described, the combination of a movable frame, guides extending at right angles to each other and having teeth extending transversely and longitudinally of the respective guides and in meshing engagement, and means for supporting the guides.
- 40 5. In a device of the class described, the combination of a movable frame, upper and lower guides extending at an angle with relation to each other and comprising a roller having peripheral teeth in meshing engagement with an adjacent guiding member, said lower guides being in contact with and forming a support for the upper guides, means for connecting the upper guides with the movable frame, and means for supporting the lower guides.
6. In a device of the class described, the combination of a movable frame, parallel guides movable with the movable frame, and guiding mechanism comprising a roller having peripheral teeth in meshing engagement with said parallel guides and forming a support therefor, and having its axis at right angles to said parallel guides.
- 60 7. In a device of the class described, the combination of a movable frame, parallel rollers movable with the movable frame, and parallel guiding members mounted independently of the movable frame and provided with guiding teeth in engagement 125 with said parallel rollers.
8. In a device of the class described, the combination of a movable frame, parallel rollers connected to and movable with the movable frame, parallel rollers mounted independently of the movable frame and having peripheral teeth in engagement with the rollers of the movable frame and forming a support for the latter, and means for securing a plate and templet or similar articles to the movable frame.
9. In a device of the class described, the combination of a movable frame, parallel rollers supported independently of the movable frame and provided with peripheral teeth, and parallel rollers connected and movable with the movable frame and having peripheral teeth parallel and in meshing engagement with the peripheral teeth of the first mentioned rollers.
10. In a device of the class described, the combination of a movable frame, toothed parallel rollers connected and movable with the movable frame, and parallel rollers supported independently of the movable frame and extending at right angles to the parallel rollers of the movable frame and having peripheral teeth in meshing engagement with the latter.
11. In a device of the class described, the combination of a movable frame, a set of 95 parallel guiding rollers connected and movable with the movable frame, and a set of parallel guiding rollers extending at right angles with relation to the first mentioned set of rollers, one set of said rollers having 100 annular peripheral teeth, and the other set of said rollers having longitudinal peripheral teeth in meshing engagement with said annular peripheral teeth.
12. In a device of the class described, the combination of a movable frame, guiding mechanism comprising a toothed roller in meshing engagement with and extending at an angle with relation to an adjacent relatively movable guiding member, and adapted 110 to permit the movement of the frame from a given position to another parallel position, and means for operating the frame.
13. In a device of the class described, the combination of a movable frame, toothed guiding mechanism connected and movable with the movable frame, toothed rotary guiding mechanism supported independently of the movable frame and extending at right angles to and in toothed supporting engagement with the first mentioned movable guiding mechanism, means for securing a templet to the movable frame, means for securing a plate or similar article to be operated upon to the movable frame and in parallel relation to the templet, and means for moving the movable frame.
14. In a device of the class described, the combination of a movable frame, a set of 120 parallel guiding rollers connected and mov- 130

- able with the movable frame, a set of parallel guiding rollers extending at right angles with relation to the first mentioned set of rollers, one set of said rollers having 5 annular peripheral teeth, and the other set of said rollers having longitudinal peripheral teeth in meshing engagement with said annular peripheral teeth, means for securing a templet or pattern to the movable frame, and means for securing a plate or similar article to said movable frame in parallel relation to the templet or pattern.
15. In a device of the class described, the combination of a movable frame, a set of 15 parallel guiding rollers connected and movable with the movable frame, a set of parallel guiding rollers extending at right angles with relation to the first mentioned set of rollers and supported independently 20 of the movable frame, one set of said rollers having annular peripheral teeth, and the other set of said rollers having longitudinal peripheral teeth in meshing engagement with said annular peripheral teeth, means 25 for securing a templet or pattern to the movable frame, means for securing a plate or other article in position to be supported and moved by the frame in parallel relation to the pattern or templet, and means for 30 moving the frame.
16. In a device of the class described, the combination of a movable frame, guiding mechanism comprising a toothed roller in toothed engagement with and extending at 35 an angle with relation to an adjacent relatively movable guiding member, a piston cylinder, a piston mounted in the cylinder and provided with a piston rod, and means for operatively connecting the movable 40 frame with the piston rod.
17. In a device of the class described, the combination of a movable frame, rotary guides extending at an angle to and in toothed engagement with each other and 45 forming a support for the movable frame, means for connecting a templet, pattern or similar article to the movable frame, means for securing a plate or other article to the movable frame in position to be moved in 50 parallel relation to the templet or pattern, a piston cylinder, means for connecting the piston cylinder with a source of fluid pressure, a piston mounted in the piston cylinder and provided with a piston rod, and 55 means for connecting the piston with the templet or pattern.
18. In a device of the class described, the combination of a movable frame, rotary guides extending at an angle to and having 60 their peripheries in contact with each other and forming a support for the movable frame, means for securing a templet or similar article to the movable frame, means for securing a plate or other article to be operated upon to the movable frame in position 65 to be moved in parallel relation to the templet, a piston cylinder, means for rotatably supporting the piston cylinder, a piston mounted in the piston cylinder, and means for operatively connecting the piston with the movable frame.
19. In a device of the class described, the combination of a movable frame, rotary guides extending at right angles to and in toothed engagement with each other and forming a support for the movable frame, a templet mounted upon the movable frame and movable therewith, means for securing a plate or other article to be operated upon to the movable frame in parallel relation to the templet, a finder movable into and out of engagement with the templet, and means for operatively connecting the finder with a source of power.
20. In a device of the class described, the combination of a movable frame, guides extending at an angle to and in meshing engagement with each other and adapted to guide the frame from a given position to another position parallel to the position from which it is moved, a templet mounted upon the movable frame and movable therewith, means for securing the templet to the frame, means for securing a plate or other article to be operated upon to the movable frame in parallel relation to the templet, a finder movable into and out of engagement with the templet, a stop for limiting the movement of the finder, and means for operatively connecting the finder with a source of power.
21. In a device of the class described, the combination of a movable frame, guides extending at right angles to and in meshing engagement with each other and adapted to guide the frame from a given position to another position parallel to the position from which it is moved, a templet mounted upon and movable with the movable frame, means for securing a plate or similar article to the movable frame in parallel relation to the templet, a finder movable into and out of engagement with the templet, means for operatively connecting the finder with a source of power, a stop for limiting the movement of the finder, and a punch mounted in a position with relation to the plate corresponding with the position of said stop with relation to the templet.
22. In a device of the class described, the combination of a movable frame, guides extending at right angles to and in meshing engagement with each other and adapted to guide the frame from a given position to another position parallel to the position from which it is moved, a templet mounted upon the movable frame and movable therewith, means for securing the templet to the frame, means for securing a plate or other article to be operated upon to the movable frame.

frame in position to be moved and supported by the frame in parallel relation to the templet, a piston cylinder, means for rotatably supporting the cylinder, a piston mounted in the cylinder, a finder connected with and adapted to be operated by the piston, a stop for limiting the movement of the finder, means for connecting the cylinder with a source of power, and a tool mounted in a position with relation to the plate corresponding with the position of said stop with relation to the templet.

23. In a device of the class described, the combination of a movable frame, guiding mechanism adapted to permit the movement of the frame from given position to another position parallel to the position from which it is moved, a piston cylinder, a piston mounted in the cylinder, a supply pipe leading to source of fluid supply, and a finder connected with the piston and adapted to be operatively connected with and disconnected from the movable frame.

24. In a device of the class described, the combination of a movable frame, guiding mechanism for guiding the frame, means for supporting the frame and guiding mechanism, means for securing a templet or pattern to the movable frame, a piston cylinder, means for rotatably supporting the piston cylinder, means for connecting the piston cylinder with a source of fluid supply, a piston mounted in the piston cylinder, a piston rod connected with the piston, a

finder connected with the piston rod and movable into and out of operative engagement with the movable frame, means for securing a plate or other article to be operated upon to the movable frame, and a stop for limiting the movement of the finder.

25. In a device of the class described, the combination of a movable frame, guiding mechanism for guiding the frame, means for supporting the guiding mechanism and thereby the frame, means for securing a templet to the movable frame, a piston cylinder, means for pivotally supporting the piston cylinder, a pipe adapted to be connected with a source of fluid supply and provided with a fluid supply passage leading to the piston cylinder, a valve for said supply passage, a piston mounted in the piston cylinder, a piston rod connected with the piston and movable into and out of operative engagement with said valve, a finder mounted on the piston rod and movable into and out of operative engagement with the movable frame, means for securing a plate or other article to be operated upon to the movable frame in parallel relation to the templet, a punch or similar tool mounted adjacent to the plate, and a stop for limiting the movement of the finder.
